UNITED STATES PATENT OFFICE.

LOUIS E. SHAW, OF EAST ORANGE, NEW JERSEY, ASSIGNOR TO WILLIAMS MOTORS INC., OF NEW YORK, N. Y., A CORPORATION OF DELAWARE.

DISK WHEEL.

Application filed May 10, 1921. Serial No. 468,225.

To all whom it may concern:

Be it known that I, Louis E. Shaw, a citizen of the United States, and residing at East Orange, county of Essex, and State 5 of New Jersey, have invented certain new and useful Improvements in Disk Wheels, of which the following is a complete specification, the particular novel features being more fully pointed out in the annexed 10 claims.

My invention relates to disk wheels for motor vehicles of the type in which a rotary cylinder motor is placed within the wheel, and where the wheel consists of two dished 15 disks facing each other with their concave sides, thus forming a housing within which the motor revolves. In wheels of this type it is desirable that one of the two disks be arranged so that it can be removed from the 20 wheel in order to mount and dismount the motor or to perform major repairs thereon.

The object of my invention is to arrange and construct the disk wheel in such fashion that the removal of one of these disk members may be conveniently and quickly accomplished by removing only one locking member, instead of unscrewing the disk member from its complementary member as has been 25 done heretofore.

My invention is illustrated in the accompanying drawings in which

Fig. 1 shows a face view of the disk wheel, a portion of one of the disk members being broken away to show the manner of coupling,

Fig. 2 shows the locking device, appearing in Fig. 1, in larger scale in closed position,

Fig. 3 shows the locking device in open 40 position,

Fig. 4 shows an inner peripheral view of the closed locking device,

Fig. 5 shows a transverse section thru the rim portion of the wheel and thru the locking device on the line 5, 5, in Fig. 2, and

Fig. 6 shows in diagrammatical fashion a transverse section thru the wheel illustrating how the motor is disposed therein.

Referring to Figures 1 and 6 the wheel 50 consists of two disks 1 and 2 being dished

and facing each other with their concave sides so that a hollow space is formed within which the revolving cylinder motor 3 is disposed. One of the disks, for instance disk 2 in Figs. 5 and 6, is permanently attached to the wheel rim 4 on which the tire (not shown) may be mounted in any suitable conventional manner. Motor vehicles having the driving motor arranged in this manner are for instance shown in the U. S. 55 patent to J. Newton Williams, No. 1,139,616 of May 18th, 1915, on which the present invention is a particular improvement.

The rim portions of disk members 1 and 2 facing each other are provided each with 60 an inwardly upturned flange portion 5 which two flange portions form, when the two disks are mounted on the wheel rim, a continuous ridge located substantially in the central plane of the wheel. I now propose to lock the two flanges 5 together by means of a U-shaped ring 6 whose sides engage the two flanges jointly, the ring being forced over the flanges 5, 5 when it is expanded as will be described presently.

This is accomplished in the following manner. As shown in Figs. 1, 2, 3, and 5 an open U-shaped ring 6 is provided, one end of which has the two shanks of the U joined together by a pivot pin 7 which 70 may be inserted into a transverse slot 8 provided jointly in the two disk flanges 5. It

may be stated at this point that the disk flanges 5 are not continuous, but are interrupted at one point where a hole 9 is provided in the periphery of the two disks (one half of the hole for each disk) which registers with a hole 10 provided in the periphery of wheel rim 4. Thru this hole the tire valve (not shown) is inserted. The slot 8 in 80 flanges 5 above referred to is located near hole 9. As is shown in Figs. 1, 2, and 3, the U-shaped ring 6 is inserted with its transverse pin 7 into slot 8 and laid over flanges 5, 5, of the disk members 1 and 2, 85 joining them. The other, free end of ring 6 has pivotally attached to it at 12 a toggle link 11, the pivotal point in the link being located intermediate its two ends as shown in Figs. 1, 2 and 3. Link 11 is preferably 90

also U-shaped as shown in Figs. 2, 3, and 5 and surrounds the U-shaped ring 6. The outer end 11^a of link 11 has its shanks connected by a pivot pin 13 which pin is adapted to engage a slot 14 provided jointly in both disk flanges 5 near the valve stem hole 9 but oppositely to where slot 8 in flanges 5 is located. If now pivot pin 13 is inserted as shown in Fig. 3 and pressure is brought to bear against the opposite end 15 of link 11 in the direction of the arrow, ring 6 will gradually be expanded and will lay itself completely over the two disk flanges 5 when the position of the toggle joint shown in Fig. 2 has been reached, in other words, when toggle link 11 has been folded over ring 6. In order to permit this folding over, a slot 16 is provided jointly in both disk flanges 5 into which pivot pin 12, by which the toggle link is attached to ring 6, sinks when the link is folded over ring 6 as shown in Fig. 2. In Fig. 1 the toggle joint is shown in closed position in full lines and in open position in dotted lines. Both disk members 1 and 2 are provided with large openings 17 near their periphery thru which the exhaust gases of the motor escape and thru which minor repairs (such as for instance exchange of spark plugs or the like) may be made. Thru one of these holes 17 the toggle joint may be conveniently opened or closed and thru these holes ring 6 may be placed in position over flanges 5, 5.

While by these means disk 1 may be removed from the wheel in order to assemble or dismantle the motor it would not be always convenient for the purpose of access to the motor to remove the entire disk 1. Therefore for the purpose of gaining limited access to the interior of the disk wheel I have provided in one of the disks, for instance in disk 1, a removable segment 18 of sufficient peripheral extension. In order to bring this segment 18 under the control of coupling ring 6, I locate this segment on the disk 1 near the point where the toggle joint is located, because when the toggle joint is opened, the toggle joint end of ring 6 is contracted first and removed from the disk flanges 5. Thus the segment becomes uncoupled from the other disk member 2 before the rest of disk 1 becomes uncoupled, and it can thus be individually removed from the wheel after the two hub screws 19 have been removed. This obviates the necessity of entirely removing coupling ring 6. The cylinder of the motor on which repairs are desired may now be turned into this opening. The position of coupling ring 6 in which segment 18 may be removed is shown in dotted lines in Fig. 1.

I claim:

1. A disk wheel consisting of two complementary disk members and means for holding said members to each other, comprising

an inwardly turned flange on each disk member forming the contact surface with the other member, a U-shaped open ring attached to the flanges of both disk members at one of its ends, and means for expanding said ring to couple the flanges of both disk members throughout their periphery. 70

2. A disk wheel consisting of two complementary disk members and means for holding said members to each other, comprising an inwardly turned flange on each disk member forming the contact surface with the other member, a U-shaped open ring attached to the flanges of both disk members at one of its ends, and means attached to the other end of said ring and cooperating with both disk flanges for expanding said ring to couple the flanges of both disk members throughout their periphery and for holding said ring in expanded position. 80

3. A disk wheel consisting of two complementary disk members and means for holding said members to each other, comprising an inwardly turned flange on each disk member forming the contact surface with the other member, a U-shaped open ring attached to the flanges of both disk members at one of its ends, and a toggle link pivotally attached intermediate its ends to the other end of said ring and having means for pivotally attaching its outer end to both of said flanges to permit the expansion of said ring by applying pressure against the free inner end of said toggle link to couple the flanges of both disk members throughout their periphery. 90

4. A disk wheel consisting of two complementary disk members and means for holding said members to each other, comprising an inwardly turned flange on each disk member forming the contact surface with the other member, a U-shaped open ring attached to the flanges of both disk members at one of its ends, and a U-shaped toggle link, pivotally attached intermediate its ends to the other end of said ring and having a transverse pivot pin at its outer end, said disk flanges having a transverse slot adapted to receive said pivot pin to provide an abutment for said toggle link on said flanges and to permit the expansion of said ring by applying pressure against the free inner end of said link, for coupling the flanges of both disk members throughout their periphery. 110

5. A disk wheel consisting of two complementary disk members and means for holding said members to each other, comprising an inwardly turned flange on each disk member forming the contact surface with the other member, a U-shaped open ring attached to the flanges of both disk members at one of its ends, and means attached to the other end of said ring and 120

cooperating with both disk flanges for expanding said ring to couple the flanges of both disk members thruout their periphery and for holding said ring in expanded position, one of said members having a removable segment located adjacent to the ring end which carries the expansion means to

permit the removal of said segment when said ring is only partially expanded, said segment being coupled to the other disk member together with its own disk when said ring is fully expanded. ¹⁰
